UNITED STATES PATENT OFFICE.

MILLER REESE HUTCHISON, OF SUMMIT, NEW JERSEY.

DESIGN FOR A CASE FOR MOVING PARTS OF MECHANICALLY-ACTUATED DIAPHRAGM-HORNS.

No. 39,785.

Specification for Design.

Patented Jan. 19, 1909.

Application filed October 8, 1908. Serial No. 456,839. Term of patent 7 years.

To all whom it may concern:

Be it known that I, MILLER REESE HUTCHISON, a citizen of the United States, residing at Summit, in the county of Union and State of New Jersey, have invented a new, original, and ornamental Design for a Case for Moving Parts of a Mechanically-Actuated Diaphragm-Horn, of which the following is a specification, reference being had to the accompanying drawing, forming part thereof.

The figure is a side elevation showing the design of the article.

I claim:

The ornamental design for a case for moving parts of a mechanically actuated diaphragm horn, as shown.

MILLER REESE HUTCHISON.
